UNITED STATES PATENT OFFICE.

EUSTIS HENRY THOMPSON, OF BALTIMORE, MARYLAND.

ERASING ATTACHMENT FOR TYPE-WRITERS.

1,232,996.

Specification of Letters Patent. Patented July 10, 1917.

Application filed March 20, 1917. Serial No. 156,157.

To all whom it may concern:

Be it known that I, EUSTIS H. THOMPSON, a citizen of the United States, residing at Baltimore, in the State of Maryland, have invented certain new and useful Improvements in Erasing Attachments for Type-Writers; and I do hereby declare the following to be a full, clear, and exact description of the invention, such as will enable others skilled in the art to which it appertains to make and use the same.

This invention relates to erasing attachments for typewriters and has for its object to provide a device of this nature which will be efficient in action and more convenient in use than those heretofore proposed.

With these and other objects in view the invention consists in the novel combinations of parts more fully hereinafter disclosed and particularly pointed out in the claims.

Referring to the accompanying drawings forming a part of this specification in which like numerals designate like parts in all the views:—

Figure 1 is a side elevational view of an erasing attachment made in accordance with this invention;

Fig. 2 is a plan view of the parts shown in Fig. 1; and

Fig. 3 is a side elevation of a modified form of the invention.

1 indicates the frame, 2 the platen, 3 the ratchet operating said platen, and 4 the ribbon of any ordinary style of typewriter. Pivoted to the typewriter frame as at 5 is the eraser frame comprising the side bars 6 and 7, the front rod or bar 8, and the depending members 9 as shown. Pivoted to said depending members 9 as at 10 are the short levers 11, carrying at their free ends the rod 12, on which is mounted the gripping member 13 of rubber or other yielding material. Leading from near each end of the rod 12 and secured thereto at one end are the flexible cords or wires 14 and 15, secured at their other end to the bell cranks 16 and 17 respectively. The frame members 6 and 7 are provided with the brackets 18 and 19 respectively in which said bell cranks are pivoted as at 20. The bell crank 16 is pivotally connected as at 21 to the core 22 of the solenoid 23, while the bell crank 17 is pivotally connected as at 24 to the core 25 of said solenoid.

Pivots mounted to the pivot rod or shaft 5 is the hand operated lever 30 provided with the extensions 31 and 32 coöperating with the T-shaped bracket 33 having the extensions 34 and 35. The extension 32 is preferably in the form of a knife switch adapted to make circuit with the contact 36 carried by the arm 6 which is connected with the wire 37 joined to the battery 38, joined to the wire 39, connected with the solenoid 23. The extension 32 is also joined to the wire 40 connected with the contact 41 adapted to make circuit with the contact 42 carried by the shaft 5, and said contact 42 is joined by the wire 43 connected with said solenoid 23. Pivoted as at 45 is the lever 46 having at one end the insulated member 47 adapted to close the contacts 41 and 42, and at its other end the forked member 48 adapted to straddle the pivot 24 and to be reciprocated by the solenoid core 25 as will be presently explained.

The lower end 48' of the lever 30 is provided with the pin 49 positioned in the slot 50 with which one end of the reciprocating member 51 is provided, and the other end of said member 51 is pivoted as at 52 to the detent lever 53 pivoted as at 54 to the frame of the machine, and provided with the detent 55' adapted to engage and disengage the ratchet 3 as will be clear from Fig. 1 of the drawings.

The forward rod or member 8 carried by the side frames 6 and 7 is provided with the depending member 55 carrying an eraser 56 preferably in the form of a rubber disk and which can be moved toward and from the platen 2 by turning the said rod 8 in its bearings and can also be slid along said rod 8, all as will be clear from the drawings.

The operation of this improved eraser attachment will be clear from the foregoing but may be briefly summarized as follows:—

Supposing 58 to represent the paper in its position around the platen 2 and supposing it is desired to erase a character or symbol which has just been impressed thereon, and which therefore lies beneath the ribbon 4. The lever 30 is thrown from its dotted line position shown in Fig. 1 to its full line position shown in said figure, whereupon the spring 60 which is connected

to said lever as at 61, will pass from the left hand side of the pivot 5, as seen in said Fig. 1, to the right hand side thereof and thus cause the side frames 6 and 7 to move from their dotted line position shown in Fig. 1 to their full line position, and said spring 60 will hold the parts in said full line position.

The gripping member 13 will contact 10 with the platen as is illustrated in its dotted line position, and the circuit having been made between the contacts 32 and 36 current will flow from the battery 38 through the wire 39, solenoid 23, wire 43, 15 contacts 42 and 41, wire 40, extension 32, contacts 35 and over wire 37 back to said battery 38. The solenoid 23 having been thus energized the two cores 22 and 25 will be sucked into said solenoid whereupon the 20 two bell cranks 16 and 17 will be turned on their pivots 20 and the two flexible cords or connections 14 and 15 will draw the rod 12 and gripping member 13 from the dotted line position shown in Fig. 1 to the full 25 line position shown therein.

The said pivoted levers 11 carrying said gripping member 13 being eccentrically mounted with respect to the platen will cause the extensions 9 of said frame members 6 and 7 to rise somewhat as the said gripping member 13 grips the surface of the platen 2, or rather as the said gripping member 13 grips the paper carried by said platen the weight of the frames 6 and 7 and 30 their associated parts serve to hold the gripping member 13 in close contact with the said paper.

In addition to the above, the extreme ends 35 of the said gripping member 13 are, as best shown in Fig. 2 extended beyond the edges of the paper 58 and they likewise cause the resilient material of the gripping member 13 to contact with the platen 2, so that a firm gripping is had on the platen and 40 paper which causes the platen to be turned as the flexible members 14 and 15 are pulled in the manner just disclosed.

As the solenoid core 25 however is sucked 45 into the solenoid its pivot 24 catches on the forked end 48 of the lever 46, turns said lever on its pivot 45 and thus moves the insulated portion 47 of said lever from its position in contact with said spring members 42 and 41, to a position out of contact there- 50 with so that the circuit is broken between said contacts 41 and 42. The spring 66 which is joined at one end 67 to said lever 46 and at its other end 68 to the frame, is so disposed that when the lever 46 is in one 55 position said spring holds said lever in such position while when the said lever is moved to its other position the said spring crosses the pivot 45 and serves to hold the said lever 46 in its other position.

60 The circuit being broken as just stated,

the springs 68' and 69 which are respectively connected with the frames 6 and 7 and the gripping member 13 now cause said gripping member to move from its full line position toward its dotted line position 65 shown in Fig. 1. But owing to the rapidity with which succeeding breaks and makes of said circuit is had said gripper does not reciprocate over an arc sufficient to permit the letter that is to be erased to return to its 70 normal position under the ribbon 4, but said reciprocations cause it to oscillate under said eraser 56 as will presently appear.

The movement of said gripping member 13 from its said full line position toward its dotted line position further causes the connections 14 and 15 and bell cranks 16 and 17 to pull the solenoid cores out of the solenoid and into the full line position shown in Fig. 2 and the corresponding movement 80 of the solenoid 25 causes the lever 46 to be swung on its pivot 45 back into the full line position shown in said Fig. 2 whereupon the circuit is again made at the contacts 41 and 42, and the operation is repeated. In other 85 words, so long as no pressure is exerted by the operator on the eraser 56 the platen 2 with the paper will first be so revolved as to bring the character in position to be erased and out from under the ribbon 4. 90 whereupon said character will be oscillated under said eraser. When the circuit is finally broken the platen will be returned to its normal position. It therefore follows that when the operator holds the eraser 56 95 over and in contact with the character to be erased, the said reciprocations of said paper and platen will cause the eraser 56 to obliterate the said character.

Of course, in addition to the above, if the 100 operator so desires he may rotate the said eraser on its pivot and thus aid the motion of the parts in erasing the character. Before the platen 2 can be thus oscillated however, it must be released from its detent 55. 105 Such release is automatically accomplished when the lever 30 is thrown from its dotted line position to its full line position shown in Fig. 1. That is to say the pin 49 reaches the end of the slot 50 in the member 51 and the said member 51 pulls the detent 55' from the dotted line position shown in said Fig. 1 to its full line position. After the character has been thus erased by throwing the lever 30 from its full line position to its dotted line position shown in Fig. 1, the extension 34 of the bracket 33 contacts with the frame member 6 on the left hand side of its pivot 5, and thus restores the parts to their dotted line positions all as will be clear 115 from said Fig. 1.

In the somewhat modified form of the invention illustrated in Fig. 3, the parts which have been just described and which are retained in said figure have received the 120

same reference numerals, while the additional parts are lettered as follows:

Pivoted as at 15 is the frame member 70 which carries the solenoid 23 and its associated parts, and it is provided as at 71 with the companion member 72 which carries the gripping member 13 as shown and to which are also connected the flexible members 14 and 15. The extension 48' of the lever 30, 10 has pivoted thereto, as at 76, the reciprocating member 77 to which is pivoted as at 78 the lever like member 79 having the thumb extension 80 and which is pivoted on the rod or bar 8 as shown. This said rod or bar 8 is 15 provided with a roller like member 81 which serves as a clamp. The frame member 6 is provided as at 82 with the member 83 which carries the clamping member 84 adapted to contact with the paper at about 120° or 145° 20 from the contact of the clamp 81, and to said member 83 is pivoted as at 85 the reciprocating member 86 provided with the slot 87 in which works the pin 88 carried by the lever 30. The operation of this said modified construction shown in Fig. 3 is as follows:—When the lever 30 is thrown from its full line position, in said Fig. 3, to its dotted line position corresponding to that shown in Fig. 1, the extension 31 of said 25 lever 30 strikes the extreme end 90 of the frame member 6 and tips said frame member together with all of its associated parts into a dotted line position, not shown, but which corresponds with the dotted line positions shown in Fig. 1.

As said frame member 6 rises a lug 91 carried thereby contacts with the member 70 and likewise causes said last named member and its associated parts to rise. The 30 spring 60 passes to the left hand side of the pivot 5 and holds the parts in their inoperative position all as was explained in connection with Fig. 1. On the other hand, when the lever 30 is thrown to its full line 35 position, shown in Fig. 3, then the circuits are closed, the solenoid 23 is excited, the bell cranks 16 and 17 cause a reciprocation of the gripping member 13, and a consequent oscillation of the platen 2, all as was explained in connection with Fig. 2. In this particular form of the invention, should a multiplicity of copies be associated with the platen member, the clamping members 81 and 82 serve to hold all of the sheets of 40 paper in place so that the said papers are firmly oscillated with the said platen 2. The clamping member 81 is held to its position by gravity as well as by the spring 60' and the clamping member 84 is carried into 45 its operative position by the movement of said lever 30 all as will be clear from the drawings.

In this modified form of construction the thumb extension 80 enables the operator to 50 merely push or pull on the same which en-

ables him to throw the lever 30 in one position or the other as he desires, and therefore, it is more convenient to operate than is the form shown in Fig. 1. The extension 96 may rest on any portion 77 of the frame 70 work, and as it is connected to the eraser member 56 it enables the operator to move said eraser member to any erasing position desired as well as to exert pressure thereon to facilitate the erasing operation.

To prevent the platen from returning to its normal position for typewriting whenever the eraser frame is raised to move a carbon sheet in or out of position for erasing, I provide a switch 100 adapted to short 80 circuit the contacts 41 and 42. This said switch 100 is joined by the wire 101 to the wire 43 and by the wire 102 to the wire 37 and thus cuts out the said contacts and switch 32 as illustrated in Fig. 2, leaving the 85 solenoid energized.

It will thus be seen that when the said switch 100 is closed the eraser frame 6, 7 may be raised or lowered at will, without disturbing the erasing position of the platen.

It is obvious that those skilled in the art may vary the details of the construction without departing from the spirit of the invention, and therefore, I do not wish to be limited to the above disclosure except as 90 may be required by the claims. What I claim is:—

1. In an erasing means for typewriters the combination of a platen; a gripping member adapted to contact with the paper on 100 said platen; means for reciprocating said gripping member and oscillating said platen and paper; and an eraser adapted to contact with said paper during its oscillating movement, substantially as described.

2. In an erasing means for typewriters the combination of a platen; a gripper disposed parallel to and extending beyond the edges of the paper normally carried by said platen; means for automatically oscillating 110 said platen and paper; and an eraser adapted to be held in contact with said paper during its oscillating movements, substantially as described.

3. In an erasing means for typewriters 115 the combination of a platen; a gripper disposed parallel to the paper normally carried by said platen; means comprising an electromagnetically operated member for automatically oscillating said platen and paper; and an eraser adapted to be held in contact with said paper during its oscillating movements, substantially as described.

4. In an erasing means for typewriters 120 the combination of a platen; a gripper disposed parallel to the paper normally carried by said platen; means comprising a solenoid and a circuit closing means governed by said solenoid for automatically oscillating said platen and paper; and an 125 130

eraser adapted to be held in contact with said paper during its oscillating movements, substantially as described.

5. In an erasing means for typewriters the combination of a platen; a gripper disposed parallel to and extending beyond the edges of the paper normally carried by said platen; a pivoted frame member supporting said gripper; means for automatically oscillating said platen and paper carried by said frame member; and an eraser associated with said frame member adapted to be held in contact with said paper during its oscillating movements, substantially as described.
- 10 6. In an erasing means for typewriters the combination of a platen; a pivoted frame; a gripper carried by said frame adapted to contact with the paper carried by said platen; an eraser carried by said frame adapted to contact with said paper; a magneto-motive means and connections for reciprocating said gripper and oscillating said platen and paper; and means for holding said frame in an inoperative position with said gripper out of contact with said paper, substantially as described.
- 15 7. In an erasing means for typewriters the combination of a platen; a pivoted frame; a gripper carried by said frame adapted to contact with the paper carried by said platen; an eraser carried by said frame adapted to contact with said paper; a magneto-motive means and connections for reciprocating said gripper and oscillating said platen and paper; and means for holding said frame in an inoperative position with said gripper out of contact with said paper, substantially as described.
- 20 8. In an erasing means for typewriters the combination of a platen; a pivoted frame; a gripper carried by said frame adapted to contact with the paper carried by said platen; an eraser carried by said frame adapted to contact with said paper; a magneto-motive means and connections comprising a circuit, contacts for making and breaking said circuit, and a solenoid in said circuit for reciprocating said gripper and oscillating said platen and paper; and means for holding said frame in an inoperative position with said gripper out of contact with said paper, substantially as described.
- 25 9. In an erasing means for typewriters the combination of a platen; a pivoted frame; a gripper carried by said frame adapted to contact with the paper carried by said platen; an eraser carried by said frame adapted to contact with said paper; a magneto-motive means and connections for reciprocating said gripper and oscillating said platen and paper; and means for holding said frame in an inoperative position with said gripper out of contact with said paper, substantially as described.
- 30 10. In an erasing means for typewriters the combination of a platen; a gripper adapted to contact with the paper carried by said platen; a magneto-motive means comprising make and break contacts for causing said gripper to continuously oscillate said platen and paper; and means for short circuiting said contacts and leaving said magneto-motive means energized for holding said platen and paper at the end of one of the oscillating movements, substantially as described.

In testimony whereof I affix my signature, in presence of two witnesses.

EUSTIS HENRY THOMPSON.

Witnesses:

GEORGE SHINNAMON,
R. L. THOMPSON.

gripper carried by said frame adapted to contact with the paper carried by said platen; an eraser carried by said frame 45 adapted to contact with said paper; a magneto-motive means and connections for reciprocating said gripper and oscillating said platen and paper; a detent for holding said platen; means connected with said frame for 50 automatically moving said detent and releasing said platen; and means for holding said frame in an inoperative position with said gripper out of contact with said paper, substantially as described.

55 9. In an erasing means for typewriters the combination of a platen; a pivoted frame; a gripper adapted to contact with the paper carried by said platen; means for holding said paper firmly on said platen; magneto-motive means for automatically reciprocating said gripper and oscillating said platen and paper; an eraser carried by said frame adapted to contact with said paper while being oscillated; and means for rendering said 60 magneto-motive means inactive at will, substantially as described.

65 10. In an erasing means for typewriters the combination of a platen; a gripper adapted to contact with the paper carried by said 70 platen; a magneto-motive means comprising make and break contacts for causing said gripper to continuously oscillate said platen and paper; and means for short circuiting said contacts and leaving said magneto-motive means energized for holding said platen and paper at the end of one of the oscillating movements, substantially as described.
